UNITED STATES PATENT OFFICE.

HUGO J. BAUR, OF CHICAGO, ILLINOIS, ASSIGNOR, BY MESNE ASSIGNMENTS, TO
JOHNSON COIN COUNTING MACHINE CO., A CORPORATION OF NEW YORK.

COIN-COUNTING MACHINE.

1,410,239.

Specification of Letters Patent. Patented Mar. 21, 1922.

Application filed November 3, 1919. Serial No. 335,311.

To all whom it may concern:

Be it known that I, HUGO J. BAUR, a citizen of the United States, and a resident of the city of Chicago, in the county of Cook and State of Illinois, have invented certain new and useful Improvements in a Coin-Counting Machine; and I do hereby declare that the following is a full, clear, and exact description of the same, reference being had 5 to the accompanying drawings, and to the numerals of reference marked thereon, which form a part of this specification.

This invention relates to a high speed coin counting machine which is adapted to 15 count predetermined numbers of coins of different denominations, according to the denomination for which the machine is adjusted, and mechanisms are provided within the machine for automatically stopping the 20 actuation of the counting mechanism after the desired number of coins has been counted. The machine also embodies novel features of handling the coins so that great numbers of coins may be accurately counted 25 within a short space of time and this is achieved by the use of mechanism handling the coins comprising a high-speed centrifugal coin receiving disk, which discharges to a slower speed carrier element and the coins 30 are carried thereby into the field of operation of the counting mechanism.

It is an object therefore of this invention to provide a high-speed coin-counting machine wherein centrifugal means are provided to distribute the coins to a coin-carrying element which thereafter transfers the 35 coins rapidly into the field of operation of a counting mechanism.

It is also an object of this invention to 40 provide a high-speed coin-counting machine wherein centrifugal mechanism operates to distribute and discharge the coins to a carrying element which in turn carries the coins into the field of operation of counting mechanisms, if desired, set to count a predetermined 45 number of coins, and thereafter said counting mechanisms are locked from further operation until again set by the operator for continuous counting or for another 50 predetermined count of coins.

It is furthermore an object of this inven-

tion to provide a high speed coin counting machine adapted for coins of different denominations, provided with centrifugal means for distributing the coins to counting 55 mechanisms and with means automatically operating to effect a predetermined count of a number of coins or permitting continuous counting thereof and registering the total number of coins passed through the machine. 60

Other and further important objects of this invention will be apparent from the disclosures in the specification and drawings.

The invention (in a preferred form) is 65 illustrated in the drawings and hereinafter more fully described.

Drawings.

Figure 1 is a top plan view of a machine 70 embodying the principles of my invention.

Figure 19 is a top plan view of the low-speed coin carrier element.

15 Figure 20 is a bottom plan of the retaining ring adapted to be fitted over the coin carrier element.

Figure 21 is a detail view taken on line 21—21 of Figure 4.

20 *Description.*

The counting machine embraces a base 1, which is cored out on the interior and is provided with a bottom 2. As shown 25 clearly in Figure 3, a top wall 3 of the base 1 has a downwardly extending circular portion 4, and journalled vertically therethrough is a shaft 5 having a bearing member 6 seated in said recessed portion 4. Secured to the under surface of the top wall 3 in any suitable manner, and disposed within the interior of the base, is a U-shaped frame 7 affording a step bearing 8 at its 30 lower portion for said shaft 5 and also provided with a bearing extension or bracket 9 at one side thereof. Secured upon the upper end of said shaft 5 is a receiving and distributing coin wheel or centrifugal disk 10 and journalled on said shaft 5 therebeh- 35 neath is a coin carrying or propelling element or disk 11, the margin of which is offset upwardly so as to surround said high-speed disk 10 and is flush therewith. Secured upon the hub of the carrier wheel or 40 disk 11 is a driving gear 12 therefor which meshes with a driving pinion 13 secured upon the upper end of an upright counter shaft 14, which is journalled in an extension 15 of the U-frame 7 and in the top wall 45 3 of the frame 1. At its lower end said shaft 14 is provided with a gear 16, which meshes with a driving pinion 17 secured upon the lower end of the shaft 5. Thus it will be seen that the high-speed disk 10 50 is driven directly from the shaft 5, and the coin carrier element 11 is driven indirectly therefrom and at a lower speed.

The shaft 5 is provided with a bevel pinion 18 secured thereon and which is driven 55 by a larger beveled gear 19 secured upon the inner end of a horizontal shaft 20. Said horizontal shaft 20 is journalled in a bearing 21 formed in the U-frame 7, and also in the bearing 9, and as shown, is provided 60 with a detachable handle 22 adapted to be

connected on the end of said shaft through an aperture in the side wall of the base frame 1. However, any suitable manual or power means may be provided for operating the drive shaft 20.

The top wall 3 of the base frame 1 is provided with an upwardly extending circular wall 23, the outer surface of which is substantially flush with the outer edge of the coin carrier wheel 11. Fitted around 75 said wall 23 and projecting upwardly therefrom is a ring 24 and adjustably mounted in said ring 24 and supported thereby and spaced above the centrifugal disk 10 and the carrier element 11 is a ring member 25 80 of channel section having a central aperture 26 through which coins are introduced into the machine upon the centrifugal disk 10. Attached over cut-away portions of said ring 24 are small plates 27, one of 85 which is shown in detail in Figure 5, and each of said plates 27 is provided with an irregular slot 28 therein adapted to receive a pin 29 which is secured upon the ring member 25, and by the position of the respective pins 29 in said slots 28, the elevation of said member 25 above said disk 10 and the coin carrier element 11 is determined. The inner upper edge of said channel member 25 is beveled, as clearly shown in 90 Figure 4, so as to permit a hopper, pan, or other means to be fitted therein for discharge of coins to the centrifugal disk, 10.

Secured in any suitable manner upon the top wall 3 of the base frame 1 at the front 100 end of the machine, is a small casing 30 cored out on its interior, as clearly shown in Figure 3, and having journalled vertically therethrough, a shaft 31, the lower end of which projects through the top wall of the base 1 and is provided with a bevel pinion 32. Secured near the upper end of the shaft 31, exterior of the casing 30, is a small bevel pinion 33, which meshes with another bevel pinion 34 on the shaft of a 105 totalizing register or counter 35, shown clearly in Figures 1 and 2, and mounted upon the upper surface of the casing 30. The upper end of said shaft 31 has attached thereon a hand knob 36 whereby 110 the register shaft 31 may be manually adjusted to set the counting wheel or registering mechanism to the position desired. Secured upon the shaft 31 within the casing 30 is a ratchet wheel 37, clearly shown 115 in Figure 6, and pivotally mounted adjacent thereto on a pintle 38 depending from the top wall of the casing 30 is a detent lever 39 provided with a roller 40 at its end for engagement with the ratchet wheel 120 37 and having a spring 41 normally impelling said lever 39 toward the ratchet wheel.

Also secured upon the register drive shaft 31 is a coin-contacting star wheel 42 130

having ten teeth on its periphery and so disposed with relation to the coin carrying element 11 as to project slightly thereover, as shown in Figures 6 and 3, with one tooth 5 of the star wheel normally resting in a recessed marginal portion 43 of said coin carrying element.

Pivoted upon a stud 44 within the casing 30, shown in Figure 6, is a lever 45 with a 10 spring 46 coiled around said stud 44, as shown in Figure 12, and connected with said lever 45 to normally impel the same outwardly away from the star wheel 42. Said lever 45 is adapted to swing inwardly beneath the star wheel 42 and is provided with an abutment portion 47, shown in dotted lines in Figure 6. Two diametrically oppositely disposed projections or stops 48 are provided on the under surface of the star 20 wheel 42, each one thereof adapted to contact with the abutment portion 47 of said lever 45 when the same is swung inwardly to thereby lock said star wheel from movement. Said lever 45 is also provided with a 25 downwardly extending tail portion 49, which extends through a cut-away portion of the top wall 3 of the base frame 1, as clearly shown in Figure 10.

Within the base frame 1 beneath the casing 30 are a pair of depending members 50, shown in detail in Figures 10, 11 and 14, and journaled therebetween is a worm shaft 51, the worm threads of which are of ratchet configuration. Secured to one end of 35 the worm shaft 51, as shown in Figure 11, is a bevel pinion 52 which meshes with the bevel pinion 32 of the register actuating shaft 31.

Another pair of depending members 53 40 are provided on the under surface of the top wall 3 of the base frame 1, and supported therebetween is a shaft 54. Pivotedly mounted upon the shaft 54 at the ends thereof, are the radial extensions or arms of a long plate 45 55, shown clearly in Figure 11, the rearward edge of which is turned downwardly as denoted by the reference numeral 56 as shown in Fig. 16, and the forward recessed edge of which is provided with a notch 57 to receive 50 the tail portion 49 of the lever 45.

Slidably mounted upon the shaft 54, as shown in Figures 10 and 16, is a cylindrical member 58, which at one end is reduced on its exterior diameter in stepped relation to 55 afford successive steps, and mounted thereon are three levers denoted respectively by the reference numerals 59, 60 and 61.

The lever 59 is pivotally mounted and at 60 its outer end is offset downwardly a slight amount below the stationary lever 60, as clearly shown in Figure 12, and is provided with a beveled edge extension 61, shown in Figure 12, which extends beneath the worm 51 and, owing to the weight of the other end 65 of said lever, said extension is normally held

upwardly in engagement with the threads of the worm. The lever 60 is provided with an upwardly extending portion or projection 62, which is adapted to contact the tail portion 49 of the lever 45 for a purpose 70 hereinafter pointed out. The lever 61 is pivotally mounted and is provided with a bent beveled end 63, shown clearly in Figure 10, and bearing on a lug projection 64 of said lever 61, is one end of a spring 65 75 coiled about a cylindrical member 66 rigidly mounted upon the reduced diameter end of the cylinder 58.

Consequently said spring acts to hold the outer end of said lever downwardly in the 80 position shown in Figure 12. Said lever 61 is also provided with a projecting portion 67, which is notched to engage with the down-turned margin 56 of the plate 55 and by movement of the lever, tilts said plate 55 85 from the position shown in Figure 12 to a position such as shown in Figure 14.

The end of the levers 59 and 60 project outwardly through a long slot 68 in a plate 69 secured upon the front surface of the base 90 1, as shown in Figures 1 and 2. An adjustable stop element is slidably mounted in the slot 68 and this comprises a stud 70, shown in detail in Figures 13 and 14, having a flange 71 to bear against the inner surface 95 of the base frame 1. A cylindrical member 72 is slidable on said stud 70 with a compression spring 73 disposed on its interior to normally hold the same thrust inwardly 100 against the plate 69, so that the clamping arrangement holds the stop element or stud 70 in any desired position in the slot 68. A V-shaped projection 74 is provided on the upper portion of said cylindrical member 72, and a plate 75 is secured over the plate 105 69, and is provided with a series of V-notches having the numbers 10—20—25—30—40—50—100 and letter "C" thereover into any one of which the V-shaped projection is adapted to fit to hold the stop stud 70 from 110 sliding movement in its slot. The inner end of said stud 70 is in a position to be contacted by the beveled end 63 of the lever 60.

Means are provided for regulating the admission of coins to the counting mechanism 115 one by one and also preventing admission thereto of coins larger than the diameter of the particular denomination of coin for which the machine is set for counting. This comprises a long lever 76 clearly shown in Figure 6, pivoted upon a stud 77, and the forward end of said lever is tapered to afford a finger which lies over the surface of the carrier element 11 in position opposite to the counting star wheel 42. The other 120 end of said lever 76 is provided with a series of apertures 78, different ones of which are adapted to register with different ones of a series of apertures 79 provided in the top wall of the base frame 1, according to the 130

5 pivotal shifting movement given to said lever 76 for the purpose. A removable plug 80 is provided adapted to be inserted through any pair of registering apertures to hold the lever 76 in any fixed desired position of adjustment with reference to the star or counting wheel 42 for coins of a certain denomination.

Means is provided to regulate the elevation 10 of the ring member 25 above the coin carrying element 11 coincident with adjustment of the lever 76, so that said ring member 25 is spaced above the coin carrier element a distance substantially equal to the thickness 15 of a coin for which the lever 76 is set. For this purpose a tail extension 81 is provided on the lever 76 and a roller 82 is mounted thereon which engages upwardly into a recess 83 therefor provided in a cutaway portion 84 of the under surface of said ring member 25, as shown in Figures 9 and 20.

20 The carrier or propeller element 11 is provided with two circular apertures 85 therethrough substantially diametrically opposite 25 one another, as shown in Figure 19, and pivoted on an extension on the under portion of the carrier element beneath each aperture, is a beveled edge pawl 86, shown clearly in Figures 7 and 8, each normally 30 impelled upwardly through its aperture by a spring 87. The coins that lay on the disk 11 in front of the pawls or studs 86 are hence positively carried and propelled past the counting wheel 42. It will be noted 35 that the counting wheel projects over the edge of the disk 11, and that the coins could not pass or escape between the lever 76 and a tooth of said counting wheel, unless some means on the disk 11 urged them past 40 the wheel. Hence the disk 11 might be termed a conveying propeller disk. As shown clearly in Figure 20, the under surface of the ring member 25 is provided with a circular groove 88, in which said projecting 45 beveled edge pawls may travel regardless of the adjustment of said member 25.

50 It should be particularly noted that my machine has the propelling conveyer disk and all operating mechanism so arranged that the same can be readily encased in the frame of the machine, making a pleasing appearance and at the same time protecting the same and preventing persons from being injured thereby.

55

Operation.

60 The machine is first set to the particular denomination of coin to be counted by inserting the plug 80 in two of a pair of registering apertures 78 and 79 so that the tapered finger end of the lever 76 is adjusted to a predetermined distance from the coin counting star wheel 42 shown in Figure 6. This adjustment of the lever 76 about its pivot 77 also effects a slight rotational ad-

justment of the ring member 25, which is supported on its three projecting pins 29 in the slotted plates 27 on the outer ring section 24, as shown in Figures 3 and 5. The adjustment of the supporting pins 29 in the slotted plates 27 determines the elevation of the ring member 25 from the carrier element 11 and centrifugal disk 10, and this distance is slightly greater than the thickness of the coin for which the lever 76 is positioned with respect to the star wheel 42.

65 The coins are dumped promiscuously into the machine through the opening 26 from a pan or any other suitable hopper provided for the purpose, and the high speed centrifugal disk 10 causes the coins to slide outwardly thereon so that the same slide singly beneath the ring member 25 and onto the upwardly offset margin of the carrier element 11, which is flush with the top surface 80 on the centrifugal disk 10. The coins distributed by the disk 10 to the carrier or propeller element 11, which is moving at a lower speed than the disk 10, are carried toward the counting wheel 42 and wedge into counting position between a tooth of the counting wheel and the end of the lever 76. Before long one of the projecting pawls 86 of the carrier element 11 moves into position back 85 of the coin, or back of a series thereof, to thrust the same past the counting wheel 42, the coin riding along on the edge of the lever 76 during its progress. Each coin serves to turn the counting wheel one tooth and overtravel or accidental adjustment 90 thereof is prevented by the spring-impelled detent lever 39 and the ratchet wheel 37. The coins as they pass the star wheel 42 are thrown off of the carrier element 11 due to centrifugal force and guided therefrom 95 by the lever 76, fall into the discharge chute 89.

100 The counting machine may be operated to count coins continuously, totaling the same upon the register 35, or may be set to 110 count the coins in predetermined groups of ten, twenty, twenty-five, thirty, fifty, or one hundred, and mechanisms then operate automatically to lock the counting wheel from further movement until the machine is 115 again set for another counting operation. When the coin-counting wheel 42 is locked from movement, or if a coin should become wedged for any reason in counting position so as to prevent the counting of other coins, 120 the projecting pawls 86, upon striking the rear edge of a coin, will be depressed against the stress of their respective springs 87 owing to the beveled surface of contact with the coin. Without undue resistance to the coin, however, the stress of the spring 87 for each pawl 86 is sufficient to force a coin or a series of coins past the counting wheel 42.

125 In order to set the counting machine to 130

count a predetermined number of coins, the lever 59 is clasped by the fingers together with the lever 60, thereby elevating the end of the lever 59 and depressing the inner extension 61 thereof, shown in Figure 14, downwardly from and out of engagement with the worm 51, whereupon, by means of said levers, the entire assembly of levers and cylinder 58 may be moved along upon 5 the rod or shaft 54. The stop 70 has been set, for instance, to the 100 mark, as shown in Figure 18, to count 100 coins and upon the assembly mentioned being shifted toward said stop, the beveled or inclined end 10 of the lever 61 strikes the stud 70 and rides thereover, thereby tilting the plate 55 inwardly. If the tail lever 49 has been in engagement with the notch 57 of said plate 55, then said tail lever is released and the 15 lever 45 swings outwardly under the impulse of its spring 46. When said lever 45 is in its inner position with the tail 49 thereof locked in the notch 57 of the plate 55, the abutment 47 on said lever 45 is in 20 the path of one of the projections 48 of the counting wheel 42, thus preventing operation thereof. When the assembly of levers 59 and 60 and 61 are moved to their 25 limiting positions determined by the position of the stop stud 70 and the lever 59 is released, the inner beveled edge end 61 thereof will again engage with the worm 51.

When a drive is imparted to the counting machine and coins are counted the successive 30 actuations of the star wheel 42 as coins move therepast serves not only to operate the register 35 to totalize the coins counted, but also to drive the worm shaft 51 through the beveled gears 32 and 52, as shown in 35 Figure 11. The speed ratios of the various gears and the pitch of the worm are such that upon the beginning of movement of the worm the lever assembly 50 and 60 and cylinder are moved along on the shaft 40 54 and at the time 100 coins have been counted, the projection 62 on the lever 60 strikes the tail 49 on the lever 45 swinging the lever 45 inwardly against the stress of the spring 46, to lock the star wheel 42 45 from further movement and the said lever 49, upon moving inwardly, first tilts the plate 55 upwardly against the stress of the spring 65 and then seats into the recess 57 and is locked from retractive movement by 50 return of the plate 55 to horizontal position. The counting wheel can now only be released by resetting the stop stud 70 to a new position and then elevating the lever 59 and moving the lever assembly along on 55 the rod 54 until the beveled end 63 strikes the stop stud 70 to tilt the plate 55 into the position shown in Figure 14 to release the tail portion 49 of the lever 45, whereupon its spring will move the same out 60 of locking position.

I am aware that numerous details of construction may be varied through a wide range without departing from the principles of this invention, and I therefore do not purpose limiting the patent granted 70 otherwise than necessitated by the prior art.

I claim as my invention:

1. In a coin counting machine, a centrifugal coin distributing disk, a conveying propeller member concentric therewith, 75 means for rotatably supporting said disk and member on the same axis, and means for rotating said disk and member at different rates of speed respectively.

2. In a coin counting machine, a counting mechanism, a rotatable coin distributing disk, a rotatable conveying and propeller ring surrounding said disk for receiving the coins, and carrying them to the counting mechanism, and means for operating said 80 disk and ring at different relative speeds.

3. In a coin counting machine, a rotatable coin distributing disk, a rotary propeller concentric therewith, a coin guiding ring surrounding said propeller, a flange member 90 adjustably supported on said ring and overhanging said propeller, and means for rotating said disk and propeller.

4. In a coin counting machine, a horizontal rotary coin distributing disk, a horizontal coin conveying and propeller ring concentric therewith, and means for driving said disk and ring at different relative rates of speed.

5. In a coin counting machine, two concentric rotatable members having their upper surfaces in the same horizontal plane, and driving means therefor.

6. In a coin counting machine, a coin counting wheel, a horizontal coin distributing disk, a horizontal coin conveying and propeller device for receiving the coins from said disk and carrying and propelling them in contact with said counting wheel, and means for driving said disk and device at 105 different relative speeds.

7. In a coin counting machine, a counting mechanism, a centrifugal coin distributing disk, a conveying propeller concentric therewith for receiving the coins and carrying them to the counting mechanism, means for rotatably supporting said disk and member upon the same axis, and means for driving the same at different relative rates of speed.

8. In a coin counting machine, a counting mechanism, a coin distributing disk, a coin propeller having a flat upper surface in the same plane as the upper surface of said disk adapted for conveying the coins to said counting mechanism, and means for operating said disk and propeller.

9. In a coin counting machine, a coin counting wheel having projections, an adjustable lever, and means comprising a rotating worm screw for adjusting said lever 130

to engage said projections to stop said counting wheel after a predetermined number of revolutions thereof.

10. In a coin counting machine, a counting wheel, a device adjacent thereto, a longitudinally adjustable stop, a longitudinally movable mechanism, and means for operating said wheel and mechanism to cause said mechanism to engage said stop and operate 10 said device to stop said counting wheel.

11. In a coin counting machine, rotary coin distributing and conveying members, a guide ring surrounding said conveying member, a flange member adjustably supported 15 on said ring, said ring having an opening for ejecting coins therethrough, a lever pivoted adjacent said opening for varying the size of said opening, and means on said lever for adjusting said flange member simultaneously with the adjustment of said 20 lever.

12. In a coin counting machine, a counting mechanism, a horizontal rotary coin distributing disk, and a horizontal propeller having yielding abutments for propelling 25 the coins into contact with said counting mechanism.

13. In a coin counting machine, a counting wheel, a rotary coin receiving and distributing device, and a horizontal propeller 30 for receiving the coins from said device, and conveying them to and projecting them past said counting wheel.

In testimony whereof I have hereunto subscribed my name in the presence of two 35 subscribing witnesses.

HUGO J. BAUR.
